PNEUMATIC TYPE PULSATORT

Myles Morgan, Worcester, and Nicholas T. Werthesen, Sherborn, Mass., assignors to Worcester Foundation for Experimental Biology, Shrewsbury, Mass., a corporation of Massachusetts

Application June 21, 1947, Serial No. 756,260

5 Claims. (Cl. 60—62.5)

1

This invention relates to pulsators, and more particularly to apparatus for supplying a pulsating gas pressure to the surface of a liquid within a surge chamber, so that the liquid may be pumped in a desired manner.

Very difficult problems are involved in the construction of pumps for use with certain liquids. For example, corrosive liquids may attack metal parts and greatly reduce their useful life. Liquids which carry abrasive particles in suspension may cause excessive wear on the parts of the pump. Still other liquids must be maintained in a sterile condition and hence must be prevented from coming contact with unsterilized parts. Furthermore, in many cases it is important to adjust and control the pressure of the liquid delivered by the pump and the rate of liquid flow, and this requirement greatly complicates the problem.

It is accordingly one object of the invention to provide a comparatively simple, inexpensive and dependable pulsator which will be capable of supplying a pulsating gas pressure of desired characteristics for use in pumping certain liquids of a difficult nature, such as corrosive liquids, abrasive-bearing liquids, or sterile liquids.

It is a further object of the invention to provide a pulsator for use as part of a liquid-pumping apparatus and so constructed that not only the pressure of the liquid delivered but also the rate of the liquid flow can be readily adjusted and controlled.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is an elevation of a pumping apparatus, with certain parts broken away for clearness of illustration;

Fig. 2 is a section taken on the line 2—2 of Fig. 1;

Fig. 3 is a section taken on the line 3—3 of Fig. 1;

Fig. 4 is a section taken on the line 4—4 of Fig. 1;

Fig. 5 is an enlarged sectional view of a valve forming a part of the apparatus shown in Fig. 1; and

Fig. 6 is a fragmentary view similar to Fig. 1 but showing a modified construction.

Referring now to Fig. 1, the embodiment illustrated comprises a suction or supply pipe 10 lead-

2

ing to a check valve 11 having a valve member 12, a connecting pipe 14 leading from the check valve 11 to a second check valve 15 having a valve member 16, and a pressure or delivery pipe 18 leading from the check valve 15 to a place of use or delivery. Each of these check valves will open to permit upward flow of liquid therethrough, and close to prevent downward flow of liquid therethrough. The two check valves are connected in series by the intermediate pipe 14 which in turn is connected by a branch pipe 19 to a surge chamber 20. These various parts are made of a material suitable for use with the particular liquid to be handled. In many cases they may be made of glass. This will withstand contact with most liquids, it can readily be sterilized if necessary, and because of its transparency it permits the operator to ascertain by visual inspection the quantity of liquid in the surge chamber 20.

In order to bring about the desired flow of liquid from the supply pipe 10 to the delivery pipe 18, there is provided a pulsator which is constructed and arranged alternately to increase and to decrease the pressure effective on the liquid within the surge chamber 20. For this purpose there is provided an expansible chamber comprising an upright cylinder 22 and a conduit 23 connecting the lower end of the cylinder to the chamber 20. Trunnions 24 project from opposite sides of the cylinder and are carried in a bracket 26 which is vertically slidable in a guideway 27 formed on a frame member 28. This frame member also carries a bearing 30 for a vertical screw 31 which is threaded through the bracket 26. A crank 32 is mounted on the lower end of the screw so that the screw may be easily rotated to adjust the bracket 26 and the cylinder 22 vertically. The conduit 23 is preferably made of rubber or other flexible material in order to permit movement of the cylinder. A piston 34 is provided within the cylinder 22, and a piston rod 35 extends upwardly from the piston and through the upper end of the cylinder.

Power actuated means is provided to reciprocate the piston rod and piston, thereby alternately increasing and decreasing the pressure of the air or other gas which is confined within the cylinder, the conduit 23 and the chamber 20. This is brought about by means of a generally horizontal lever 37 one end of which is pivotally connected by a pin 38 to a pair of blocks 39, these blocks being slidable in vertical guide slots 41 formed in the frame member 28. The upper end of the piston rod 35 is pivotally connected to

the lever 37, near the pin 38, by means of a pin 42. The other end of the lever is pivotally connected by means of a pin 43 to the upper end of a rod 45. The lower end of this rod is attached to the crank pin 46 of a crank shaft 47, this shaft being supported in a bearing 48 and rotated at a desired speed by a suitable motor or other means (not shown). The lever 37 is provided intermediate its length with a longitudinally extending slot 50 having a block 51 slidable therein. This block is pivotally supported on a pin 52 carried by a bracket 54, and the bracket is slidably mounted in a horizontal guideway 55 formed by a frame member 56. This frame member carries a bearing 58 for a horizontal screw 59 which is threaded through the bracket 54. A crank 60 is mounted on one end of the screw 59 so that the screw can be easily rotated to adjust the bracket 54 and the pin 52 horizontally. The pin 52 forms a fulcrum for the lever, and by adjusting the position of this fulcrum the operator may vary the length of the stroke of the piston 34.

The operation of the apparatus as so far described will now be apparent. The revolving crank shaft 47, acting through the rod 45, will rock the lever 37 about its fulcrum 52, thus alternately raising and lowering the piston 34. At each downward stroke of the piston, the air confined within the lower portion of the cylinder 22, the conduit 23, and the chamber 20 will be compressed, thereby increasing the pressure on the liquid within the chamber 20. Consequently some of the liquid will be forced upwardly through the check valve 15 and the delivery pipe 18, while the check valve 11 remains closed. At each upward stroke of the piston, the volume of the confined air will be increased until a sub-atmospheric pressure or partial vacuum is obtained, whereupon liquid will be drawn upwardly through the supply pipe 10 and the check valve 11 into the chamber 20, while the check valve 15 remains closed. Thus there will be a pulsating flow of liquid upwardly through the pipes 10 and 18, and none of this liquid will come into contact with the cylinder 22 or the piston 34. By turning the crank 32 the operator can raise or lower the cylinder 22, thereby varying the distance between the lower end of the cylinder and the piston without changing the length of the piston stroke. By turning the crank 60 he can vary the length of the piston stroke without changing the position of the cylinder. These two adjustments make it possible for the operator to obtain any desired combination of vacuum and pressure, as may be required to match the resistance to liquid flow in the pipes 10 and 18, thereby preventing appreciable variations in the quantity or level of liquid in the chamber 20.

There will ordinarily be a slight leakage of air upwardly past the piston 34 as it approaches its lower limit of travel, which will tend to reduce the weight of the air being acted upon by the piston and to change the pressure conditions throughout the cycle. In order to prevent any such change, we provide means to admit additional air to the cylinder automatically in the amounts required to make up for leakage and to maintain predetermined pressure conditions. Two arrangements of apparatus for accomplishing this result are shown and will now be described.

In Fig. 1 there is illustrated a conduit 62 which leads from a suitable supply of compressed air to the lower end of the cylinder 22, a portion 63 of this conduit being constructed of rubber or other

flexible material to permit movement of the cylinder. Along the conduit 62, and in the order mentioned with relation to the direction of flow, there are provided a shut-off valve 65, a pressure reducing and regulating valve 66, a branch provided with a shut-off valve 67, a branch provided with a pressure gauge 69, a shut-off valve 70, and a make-up valve 71. As shown in Fig. 5, the make-up valve 71 comprises a poppet-type valve member 73 having a stem 74 which extends downwardly through a stuffing box 75 and carries a button 77 on its lower end. A coiled compression spring 78 biases the valve member 73 toward its closed position. As indicated in Fig. 1, this make-up valve 71 is located directly above the lever 37 and in such a position that the right hand end of the lever will strike the button 77 and open the valve for an instant as this end of the lever reaches its uppermost position. At this time the piston 34 will be at its lowermost position, and the air within the cylinder 22 will be at its maximum pressure. Normally, the valve 65 and 70 will be open, and the valve 67 will be closed. The regulating valve 66 will be adjusted to maintain an air pressure anterior to the make-up valve 71 corresponding to the pressure desired within the cylinder 22 when the piston reaches the end of its downward or compression stroke. Consequently, if any air has escaped past the piston, the valve 71 will admit just enough air at each cycle to make up for this loss. The valve 67 is used merely to allow some air to escape from the conduit 62 as may be necessary or desirable when adjusting the regulating valve 66 for the required pressure. The pressure will of course be indicated by the gauge 69.

In Fig. 6 there is shown a modified construction for supplying make-up air to the cylinder 22. In this embodiment there is provided a Marriot tube 80 comprising a vertically elongated receptacle 81, preferably of glass, containing a body 81 of water or other suitable liquid and closed at its upper end by a rubber stopper 82. A tube 84 extends downwardly through the stopper and into the water 81, the upper end of this tube being open to the atmosphere. A tube 85 extends downwardly through the stopper and into the air space above the surface of the water 81, the outer end of this tube being connected through a check valve 87 and a conduit 88 to the lower end of the cylinder 22. The check valve includes a valve member 89 which will close automatically to prevent air flow in a direction toward the receptacle 80. The conduit 88 is formed of rubber or other flexible material to permit movements of the cylinder. Water may be added to the receptacle 80 from an elevated tank 91 which is connected to the lower end of the receptacle by a rubber tube 92 provided with a shut-off clamp 93, and water may be withdrawn from the receptacle through a rubber tube 94 provided with a shut-off clamp 95. The height of the water 81 above the lower end of the tube 84 should be such as to create a pressure head which will correspond to the degree of vacuum desired in the cylinder 22 when the piston reaches the top of its stroke. If any leakage occurs upwardly past the piston 34 during the pressure part of the cycle, this will reduce the weight of the air within the cylinder and thereby tend to increase the vacuum which will be attained as the piston reaches the top of its stroke. In such case however, upon even the slightest increase in this vacuum beyond the desired value, air will flow through the tube 84, upwardly through the body of water 81, and thence through

the check valve 87 and the conduit 88 to the cylinder 22 to replace the air which has escaped. During the pressure portion of each cycle, the check valve 87 will prevent reverse flow of air.

It will be apparent that the invention provides a relatively simple pulsator which is capable of supplying a pulsating gas pressure and controlling the maximum and minimum values of such pressure in a far more satisfactory manner than any mechanism heretofore known.

Having thus described our invention, what we claim as new and desire to secure by Letters Patent is:

1. An apparatus for supplying a pulsating gas pressure to the surface of liquid within a surge chamber connected to a conduit intermediate two check valves, the said apparatus comprising two relatively reciprocable elements forming an expansible chamber containing gas, means to reciprocate one of said elements relative to the other element and thus alternately compress and expand the gas, means to adjust the length of stroke of the reciprocating element, and independently operable means to effect a relative adjustment in the positions of the said other element and the path of the reciprocating element.

2. An apparatus for supplying a pulsating gas pressure to the surface of liquid within a surge chamber connected to a conduit intermediate two check valves, the said apparatus comprising two relatively reciprocable elements forming an expansible chamber containing gas, means to reciprocate one of said elements relative to the other element and thus alternately compress and expand the gas, means to adjust the length of stroke of the reciprocating element, and independently operable means to effect an adjustment in the position of the said other element and thereby vary its position relative to the path of the reciprocating element.

3. An apparatus for supplying a pulsating gas pressure to the surface of liquid within a surge chamber connected to a conduit intermediate two check valves, the said apparatus comprising a cylinder containing gas, a piston reciprocable in the cylinder, means to reciprocate the piston and thus alternately compress and expand the gas, means to adjust the length of stroke of the piston, and independently operable means to adjust the position of the cylinder relative to the path of the piston.

4. An apparatus for supplying a pulsating gas

pressure to the surface of liquid within a surge chamber connected to a conduit intermediate two check valves, the said apparatus comprising two relatively reciprocable elements forming an expansible chamber containing gas, a lever, a fulcrum for the lever, means to rock the lever about the fulcrum, means connecting the lever to one of the said elements to reciprocate the same relatively to the other element and

thus alternately compress and expand the gas, means to adjust the position of the fulcrum along the lever and thereby change the length of stroke of the reciprocating element, and independently operable means to adjust the position of the said other element relative to the path of the reciprocating element.

5. An apparatus for supplying a pulsating gas pressure to the surface of liquid within a surge chamber connected to a conduit intermediate two check valves, the said apparatus comprising a cylinder containing gas, a piston reciprocable in the cylinder, a lever, a fulcrum for the lever, means to rock the lever about the fulcrum, guide means to prevent longitudinal movement of the lever, a rod connecting the lever to the piston to reciprocate the same and thus alternately compress and expand the gas, means to adjust the position of the fulcrum along the lever and thereby change the length of stroke of the piston, and independently operable means to adjust the position of the cylinder in a direction longitudinal thereof.
